FUEL PUMP

William A. Ray and William R. Ray, San Francisco, Calif., assignors to General Controls Company, a corporation of California

Application December 11, 1935, Serial No. 53,920

1 Claim. (Cl. 103—37)

This invention relates to fuel pumps, particularly a pump for supplying oil under pressure to an oil burner utilized in a furnace.

In domestic heating installations, the supply of oil to an oil burner presents a problem which is quite difficult inasmuch as one must provide an installation which does not need attention. Since the flow of oil will vary with the temperature thereof and since a substantially constant amount of oil must be supplied to the burner to secure a proper combustion and an adequate heat supply, resort has been had to various control systems and to various installations some of which are shown in the prior patents of William R. Ray as Patent 1,791,012 of February 2, 1931, 1,701,191 of February 5, 1929, 1,670,741 of May 22, 1928 and 1,657,807 of January 31, 1928.

In accordance with the present invention we provide a fuel pump construction and a system for supplying an oil burner with oil in such a fashion that the supplying of a substantially constant quantity of oil is possible. Further, in accordance with the present invention, we have provided a fuel pump permitting ready adjustment to any one of various operating conditions apt to be encountered in installing a fuel oil burner.

It is in general the object of the present invention to improve upon fuel oil supply systems for domestic fuel oil burner installations.

Another object of the present invention is to provide a novel fuel pump construction.

A further object of the present invention is to provide a pump construction enabling a substantially constant quantity of oil to be supplied to a fuel oil burner in a domestic installation.

The invention includes other objects and features of advantage, some of which, together with the foregoing, will appear hereinafter wherein the present preferred form of fuel pump of our invention and the system for supplying fuel oil to a burner is disclosed.

In the drawings accompanying and forming a part hereof, Figure 1 is a side view, partly in section, to a fuel pump of our invention.

Figure 2 is a section taken along the line 2—2 of Figure 1 while Figure 3 is a section taken along the line 3—3 of Figure 1.

Briefly stated, in the present invention, we provide a fuel oil supply system for a fuel oil burner comprising a first pump which draws oil from a storage tank and discharges into a vessel. A second pump is provided for withdrawing oil from this vessel, surplus oil returning to the supply tank through an overflow line. Means are

provided for driving the second pump at a closely regulated rate so that an exact rate of fuel oil supply can be secured.

To simplify construction we provide a casing 6. This can be a die casting having a flange 7 extending from the side wall of the casing to receive a flange 8 on a sheet metal base 9.

Mounted within the casing and attached thereto is a first gear pump 11. An inlet pipe 12 from a fuel oil supply tank (not shown) communicates with intake 13 of the pump. This pump includes a driving gear 14 mounted on drive shaft 16 and a driven gear 17 mounted upon idler shaft 18. The pump discharges through outlet 19 into a sump provided by casing 6 and base 9. An overflow pipe 21 leads back from the casing to the fuel oil supply tank.

A motor 22 is mounted upon the top of the casing and carries a V belt pulley 23. This pulley, in conjunction with a suitable V belt drives V belt pulley 24 mounted upon drive shaft 16 of pump 11. In practice the first gear pump is driven at a relatively high rate, say to supply forty gallons per hour to the sump provided by casings 6 and 9.

For discharging oil a second gear pump 31 is provided. This pump draws in oil through inlet 32 from within the casing and discharges the oil through outlet 33 directly to a fuel oil burner (not shown).

For driving of the second fuel pump a drive shaft 36 extends from the side of the casing and carries a V belt pulley 31. This pulley is adapted to cooperate with a pulley 38 on the motor drive shaft to provide a plurality of speed changes, each of the pulleys being stepped in a complementary manner. Shaft 36 within casing 6 carries gears 39 and 40 pinned thereto. These gears are of a different size and cooperate with idler gears 41 and 42 mounted upon counter-shaft 43. Each idler gear includes a notch 44 to receive a projection 46 on a collar 47. Collar 47 is splined to counter-shaft 43 and is slidable by means of fork 48 to engage a projection 46 with notch 44 on either of the idler gears.

The fork 48 engages the collar and, with rod 51, provides a shifting means. Rod 51 is carried in plate 52. This plate includes slots 53 engaging studs 54 to permit a sliding to the right or left of the fork.

Also mounted upon the counter-shaft 43 are idler gears 57 and 58 cooperating with gears 59 and 61 keyed to pump drive shaft 62. This shaft carries driven gear 63 in the pump, the shaft being supported between the casing for pump 31 and the

casing for pump 11. Idler gears 57 and 58 include notches 64 which are engaged by projections 66 in a selective manner, the projections being mounted upon a slidable collar 67 splined to shaft 43. A fork 68 is provided for sliding the collar, a rod 69 and a plate 71 cooperating with studs 72 in a manner similar to that previously described in connection with the shifting of collar 48 between gears 41 and 42.

10 In operation, with motor 22 revolving, the pump 11 is driven at a rate sufficient to supply oil at about forty gallons per hour. The various speed change mechanisms provided for the driving of the pump 31 permit of sixteen selective different speeds so that pump 31 can be utilized to supply oil at almost any desired rate without having to tear apart the whole pump structure and change any gears in the pump or gears in the casing proper. The sixteen different driving speeds are secured by changing the position of the belt used to connect the multistep pulleys 37 and 38, four different driving speeds being thus provided. As appears in Figure 2, countershaft 43 is driven by gear 41 enmeshed with gear 39 when plate 52 is 15 in the position shown. When plate 52 is moved to the right to engage gear 46 with gear 44, the countershaft is driven at a different speed, gear 42 being enmeshed with gear 40. This change provides two additional speeds. Two further 20 speed changes are provided by sliding plate 71 from that position in which it appears in Figure 2 to the right in Figure 2 so that gear 66 engages gear 58 and gear 61, enmeshed with gear 59, is driven in place of gear 59. By selectively 25 changing the belt connecting pulleys 37 and 38 and by selectively sliding plates 52 and 71 to either the right or the left the sixteen different speeds 30 can be secured.

The size of pump 11 relative to pump 31 is 35 generally such that pump 11 supplies far more

oil than is necessary, the excess being returned through the overflow line. In practice, the pump such as described is set very close to the burner so that pump 31 discharges directly into the burner through its connecting line, thus simplifying the installation. 5

It is to be noted that the gear pump 31 is operated at such a speed that slippage therein is substantially absent. Therefore, by controlling the speed of the pump any desired displacement 10 is available and fuel oil can be supplied to an oil burner at a desired rate independently of oil viscosity, the pump 31 acting to measure the fuel. Thus we have eliminated the necessity for the complicated systems used heretofore to offset the 15 effect of viscosity, since the pump 31 is so situated and the system is such that the effect of viscosity is absent. Instead of a gear pump a piston type can be used although this type of pump involves the use of more parts. 20

We claim:

A fuel oil burner supply unit comprising a casing, a motor on said casing and having a power take off at each end thereof, a first pump in said casing for pumping oil into the casing and including a shaft extending out of said casing for driving from one of said power take offs, a second pump in said casing for pumping oil therefrom, and variable speed means provided between said other power take off and said second pump and 25 including a driven shaft extending out of said casing and carrying a multi-step pulley cooperating with a like pulley on said other power take off, a countershaft in said casing, and variable speed gear means for driving said countershaft from 30 said driven shaft and for driving said second pump from said countershaft. 35
